TOY PISTOL

Jack H. Wright, Chicago, Ill., assignor of one-half to Nat Brenner, Chicago, Ill.

Application January 29, 1945, Serial No. 575,039

5 Claims. (Cl. 46—192)

This invention relates to a toy pistol having a trigger and means operable thereby to cause a report in simulation of the firearm it is intended to resemble. More particularly it has relation to a toy as described comprised principally of parts molded from plastic composition.

Heretofore toy guns have been made entirely of metal and in two halves joined along the medial axis, there being slots in one half engaged by tongues in the other half, or the halves are sometimes made as described and further joined by bolts or screws. Such constructions have not met with favor as the halves may easily become detached or broken, thus rendering the toy unfit for use.

The principal object of my invention is the provision of a toy pistol comprised almost entirely of plastic composition and having only a small spring made of metal whereby to economize in the use of metal and to provide a toy having much greater durability than prior toy pistols.

Another object is to provide a toy pistol as aforesaid in which the barrel and handle are preferably integral and made in two halves accurately mated together, pinned by dowels, and welded plastically.

A further object is the provision of report-making mechanism which comprises a minimum number of parts and which, when operated, simulates to a great degree the report made by a real pistol.

Another object is to provide in connection with a mechanism as aforesaid a trigger member to actuate the free end of a reed fixed at the other end to the pistol and to release the reed to cause it to strike the trigger member with a hammer-like blow and thus accentuate the report.

Other and further objects will appear from the description and drawing, in which latter:

Fig. 1 is a side elevational view having a portion of one half of the pistol broken away to reveal the interior construction;

Fig. 2 is a plan view of the pistol;

Fig. 3 is a cross sectional view taken on the line 3—3 of Fig. 1; and

Fig. 4 is a detail view of a portion of the operating mechanism showing two of its positions.

Referring to Figs. 1 and 2, the pistol comprises a handle 10 and a barrel 11 preferably formed integrally therewith, the exterior contour thereof being shaped and embossed in simulation of a pistol of the automatic type. The handle 10 and barrel 11 are formed in two halves 12 and 13, the line of junction being in-

dicated at 14 (Fig. 2). Located about the periphery of the surface of the joint 14 are apertures 15 adapted to receive dowel pins 16 whereby to position the halves 12 and 13 in accurate alignment. It will be obvious that the dowel pins 16 may, if desired, be integrally cast with a half 12 or 13, the other half having the apertures 16. After the interior mechanism to be detailed hereinafter is assembled within the pistol the halves 12 and 13 are positioned relatively to each other and either cemented or plastically welded together to form a rigid, non-separable unit.

In each of the halves 12 and 13 there is formed a recess 21 together comprising a mortise 22 (Fig. 3) through which extends the trigger portion 23 of the member 24. A guard 25 preferably formed integrally with one of the halves 12 or 13, in this case 12, is provided as shown. The member 24 is reduced in thickness as at 26 and is provided therethrough with a pivot 27 adapted to rotate in apertures 28 in bosses 29 provided interiorly of the halves 12 and 13, the faces of said bosses providing relatively large areas of support to maintain the member 24 in proper vertical alignment indefinitely. A torsion spring 31 restrained at one end upon the inner surface of the half 12 and at the other end against the member 24 serves to urge the member 24 in a clockwise direction (as viewed in Fig. 1).

The member 24 is provided with a pair of nibs or projections 32 and 33, the nib 33 being brought to a sharp edge 34 as shown. Received in slots 35 in the halves 12 and 13 is one end 35 of a flat reed or resilient member 36, the latter being cemented in place within the slots 35. The reed 36 is beveled at its free end to provide a sharp edge 37 normally underlying the edge 34, and is substantially thicker at its free end 40 for a purpose to appear. Reed 36 may be of metal or plastic composition suitably reinforced with fabric, e. g., Formica.

In operation the child will operate the trigger 23 as in the case of a real pistol to rock the member 24 about its pivot 27 and against the force of the spring 31, whereupon the nib 33 will be brought against the free end of the reed 36 (Fig. 4). Further movement of the trigger 23 will actuate the reed 36 to the dotted line position whereat the edge 34 is just touching the edge 37. Additional movement dislodges the edge 34 from the edge 37 to permit the reed 36 to return toward normal position by reason of its resiliency. However, at that instant the nib 32 lies closely above the end of the reed 36

and is struck thereby with a hammer-like blow. Release of the trigger 23 will then permit both the reed 36 and the member 24 to return to normal position as shown in Fig. 1 in readiness for the next operation, the spring 31 serving to return the member 24.

Inasmuch as the release of the reed 36 by the nib 33 is instantaneous the trigger 23 may be operated as frequently as desired so that the toy has a rapid fire characteristic typical of the real pistol it is intended to simulate.

While I have shown particular embodiments of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. A toy pistol comprising a barrel and a handle joined thereto, said barrel having a cavity therein for receiving a trigger member and a resilient element, said member being pivotally supported within said barrel and said element being fixed at one end within said barrel; a pair of projections extending from said member, one projection being shorter than, and positioned below the other, the trigger pull lying between the pivot and the said projections, said lower projection being adapted, upon operation of said member, to actuate the free end of said element to a tensioned position and to release the same for return to an untensioned position, the element upon said return striking said upper projection to yield a report in simulation of the firing of a real pistol.

2. A toy pistol comprising a barrel and a handle, a member pivotally supported on the pistol and including a trigger normally positioned with said trigger in position to be operated, resilient means to maintain said trigger in said normal position, an elongated resilient element fixed at one end to the pistol and having its free end adapted to be actuated by said member, a pair of projections on said member, one said projection being shorter than and situated below the other, the shorter projection being adapted upon operation of said trigger for firing to displace the free end of said element from normal untensioned position to tensioned position and to release the same for return to normal position, the free end of said element, upon release thereof, striking the other projection to yield a report in simulation of the firing of a real pistol.

3. A toy pistol comprising in combination a barrel and a handle, said barrel having a cavity therein, a member within said cavity and pivotally supported on the pistol, said member having a trigger portion extending exteriorly of the cavity, resilient means normally urging said member to a position ready for firing, an elongated resilient element fixed at one end to the barrel, said member including a pair of projections, one of said projections being shorter than and disposed below the other projection, said shorter projection having a wedge-shaped extremity and said element having a wedge-shaped extremity at its free end adapted to be engaged by said first mentioned extremity when said member is operated by said trigger, whereby upon predetermined movement of said member said element is deflected from untensioned position to a tensioned position and upon further movement of said member said element is released from tensioned position to strike the upper projection to produce a report in simulation of a real pistol.

4. A toy pistol comprising a barrel and a handle joined thereto, said barrel having a cavity therein for receiving a trigger member and a resilient element, said member being pivotally supported within said barrel, and said element being fixed at one end within said barrel, a pair of projections extending from said member, one projection being shorter than the other, the trigger pull lying between its pivot and the said projections the shorter projection being adapted, upon operation of said member, to actuate the free end of said element to a tensioned position and to release the same for return to untensioned position, the element upon said return striking the longer projection to yield a report in simulation of the firing of a real pistol.

5. A toy pistol comprising a barrel and a handle joined thereto, a resilient element fixed at one end to the pistol, means including a trigger and a pair of projections, the trigger pull lying between its pivot and the said projections one projection being shorter than the other, the shorter projection being adapted, upon operation of said trigger, to actuate the free end of said element to a tensioned position and to release the same for return to untensioned position, the element upon said return striking the longer projection to yield a report in simulation of the firing of a real pistol.

JACK H. WRIGHT.
